UNITED STATES PATENT OFFICE.

EDWARD EWING, OF PHILADELPHIA, PENNSYLVANIA, ASSIGNOR TO
ROBERT E. HASTINGS, JOHN V. HASTINGS, AND HARRY O. HAST-
INGS, ALL OF SAME PLACE.

METHOD OF BOOKING GOLD-LEAF.

SPECIFICATION forming part of Letters Patent No. 311,823, dated February 3, 1885.

Application filed May 10, 1884. (No specimens.)

To all whom it may concern:

Be it known that I, EDWARD EWING, a subject of the Queen of Great Britain and Ireland, and a resident of Philadelphia, Pennsylvania, have invented certain Improvements in Booking Gold-Leaf, of which the following is a specification.

The object of my invention is to produce a book of gold-leaf in which the sheets of gold and paper adhere so firmly that there will be no liability of the gold leaf being blown off when the gilder is working in exposed localities, the adherence of the gold-leaf to the paper not being such, however, as to prevent the ready separation of the two when the gold-leaf has been applied to the sized surface. In other words, while the gold-leaf adheres so firmly to the paper as to prevent its accidental removal by a current of air, it will adhere 20 with greater tenacity to the size which covers the surface to be ornamented.

In booking gold-leaf the thin leaves of gold are placed on pieces of paper, which serve as a medium whereby the gold can be readily handled and applied to the sized surface. Usually the gold-leaf has no tendency to adhere to the sheet of paper, and consequently it is difficult, if not impossible, for a gilder to work with facility in situations where exposed 25 to currents of air, the gold-leaf being disarranged or blown away before it can be applied to the sized surface. Gilders have for many years attempted to overcome this annoyance by waxing or greasing pieces of paper and then applying these waxed or greased pieces of paper to the gold-leaf; but the difficulty of preparing the paper evenly, and the tendency of the gold-leaf to adhere to the greasy paper rather than to the sized surface, made the process 30 very imperfect and attended with a large percentage of loss of the gold-leaf. Another plan recently practiced is to dry the pieces of paper thoroughly before applying them to the gold-leaf; but this plan is also objectionable

on account of the care which must be exercised in properly drying the pieces of paper, and maintaining them in this condition. Hence, in order to provide a simpler and more practicable plan of effecting the desired result, I moisten with water the thin sheets of paper on which the gold-leaf is laid in making the book, and I find that if the water is slightly acidulated the objections to the moistened sheets are effectually overcome, and a book can be produced in which the degree of adherence of the gold-leaf and pieces of paper is just about what is desired. Sulphuric, oxalic, or other acids may be used, the quantity depending upon the strength of the acid. In practice I have used a solution of one tea-spoonful of sulphuric acid to a pint of water with good results; but this proportion need not be adhered to, the essential feature of the invention being the acidulating of the water used in moistening the pieces of paper.

In order to effect a thorough and uniform moistening of the pieces of paper, I prefer to place a number of them between sheets of thick paper saturated or moistened with the acidulated water; but this plan is not absolutely necessary.

I claim as my invention—

As an improvement in booking gold-leaf, the mode herein described of effecting the desired adherence of the leaves of gold and paper, said mode consisting in first moistening and acidulating sheets of paper, and then forming the book by alternate leaves of gold and such moistened and acidulated sheets of paper, as set forth.

In testimony whereof I have signed my name to this specification in the presence of two subscribing witnesses.

EDWARD EWING.
